John W. Maypin.
ATTORNEY

UNITED STATES PATENT OFFICE.

ASAICHI NAKAHARA, OF SEATTLE, WASHINGTON.

DAUBER BRUSH.

Application filed March 17, 1923. Serial No. 625,856.

To all whom it may concern:

Be it known that I, ASAICHI NAKAHARA, a subject of the Emperor of Japan, residing at Seattle, in the county of King and State 5 of Washington, have invented a new and useful Dauber Brush, of which the following is a specification.

My invention relates to improvements in dauber brushes and the principal objects of 10 my invention are to provide a dauber brush with a handle serving as a reservoir in which the semifluid substance is carried in a collapsible tube with means for causing said substance to be forced outwardly to the bristles of the brush for constant and convenient 15 use and means for controlling the passage and supply of said substance at all times. For the purpose of illustration, I have confined myself to a shoe brush but it will be 20 understood that the device is equally adaptable to all brushes used for the application of fluids and semifluids.

With the above and other objects in view which will appear as the description proceeds, the invention consists of the novel 25 construction, adaptation, arrangement and combination of parts hereinafter described and claimed.

These objects are accomplished by devices illustrated in the accompanying drawings, wherein—

Figure 1 is a view in side elevation of a dauber brush embodying the exterior features of the invention;

Fig. 2 is a view in horizontal section taken substantially on a broken line 2, 2 of Fig. 1;

Fig. 3 is a view in longitudinal vertical section taken substantially on a broken line 3, 3 of Fig. 2;

Fig. 4 is a view in transverse vertical section taken substantially on a broken line 4, 4 of Fig. 3; and

Fig. 5 is a view in transverse vertical section taken on a broken line 5, 5 of Fig. 1.

Referring to the drawings throughout which like reference numerals are used to designate like parts, the numeral 5 designates the head of a dauber shoe brush having an annular shoulder 6 on its side. Extending in a direction normal to the axis of said head and the brush proper is a trough 7 which is substantially semi-circular in cross section and is rigidly secured at its inner end to said annular shoulder. A cylindrical handle 8 is arranged to fit snugly over said trough and is securely held on said an-

nular shoulder by a pin 9 working in an L-shaped slot 10. A longitudinal slot 11 extends the greater length of said handle diametrically opposite said trough and a 60 clip 12 is provided near the outer end of said trough for reasons more fully described hereinafter.

A bypass 13 threaded on its outer end extends concentrically through the annular 65 shoulder 6 and into the head 5 where it communicates with an opening 14 extending vertically through said head.

The lower end of the head 5 is provided with a dauber brush 15 which is threadedly 70 secured to said head and an opening 16 extends centrally through same and registers with the opening 14. A spreader brush 17 is adapted to fit on the upper end of said head by means of an annular shoulder 18 75 and a corresponding socket.

A depending valve stem 19 is concentrically formed on the shoulder 18 and is adapted to fit snugly within the openings 80 14 and 16 as clearly shown in Figs. 2, 3 and 4 of the drawings. Said valve stem extends through said openings and partly through the bristles of the brush 15. A groove 20 is provided in said stem normally extending from above the bypass 13 throughout its 85 entire length.

In using the device the handle 8 is removed and a collapsible tube 21 is placed in the trough 7 with its neck 22 screwed into the bypass 13 and its opposite end bent 90 under the clip 12 to prevent same from slipping. A ball 23 is then pressed into place against the closed end of said tube and the handle 8 is installed and secured in place by means of the pin 9 and slot 10. 95

The ball 23 projects slightly within the longitudinal groove 11 and it will be obvious that the device is now ready for use. The brush 17 is turned until the groove 20 of the valve stem 19 registers with the bypass 100 13. By pressing the ball 23 forward with the thumb along the groove 11 the contents of the tube 21 will be forced outwardly through the bypass 13 and downwardly through the groove 20 to the bristles of 105 the brush 15.

The paste is then applied to the shoe or other object by the brush 15 in the usual manner and may be spread over the entire shoe by the brush 17. It will be obvious 110 that the supply of paste may be regulated by turning the brush 17 carrying the valve

19 and may be entirely cut off by turning said valve far enough to close the bypass 13.

5 While I have limited the description and drawings to a dauber brush for the application of shoe polish, it will be apparent that the same principle may be used for many other brushes employing fluids or semi-fluids such as shaving brushes, tooth brushes and the like.

10 From the foregoing description taken in connection with the accompanying drawings the form of construction and method of operation of my dauber brush will be readily apparent to those skilled in the art 15 to which the invention relates, and it will be understood that the apparatus shown is merely illustrative and that such changes may be resorted to as are within the scope and spirit of the invention.

20 Having thus described my invention what I claim and desire to secure by Letters Patent is:—

A brush of the character described com-

prising a head having a vertical opening therethrough, an annular shoulder on said head having a bypass therein communicating with said vertical opening, a semi-cylindrical trough secured to said shoulder, a collapsible tube having its neck threadedly secured in said bypass and its opposite end secured by a clip adjacent the outer end of said trough, a hollow cylindrical handle adapted to fit over said trough and tube having a longitudinal slot therein, means for securing said handle to said shoulder, a 35 dauber brush threadedly secured to said head having a central opening therethrough adapted to register with said vertical opening, a valve projecting through the said openings in said head and dauber brush, and a ball within said hollow handle adapted to be manually pressed against said collapsible tube through said longitudinal slot to force its contents through said head to said dauber bristles.

ASAKICHI NAKAHARA.
